UNITED STATES PATENT OFFICE.

GIROLAMO SOLDANI, OF SPENCER, MASSACHUSETTS.

ICE-CREAM-CONE DISPENSER.

1,373,986.

Specification of Letters Patent.

Patented Apr. 5, 1921.

Application filed October 9, 1918. Serial No. 257,448.

To all whom it may concern:

Be it known that I, GIROLAMO SOLDANI, a citizen of the United States of America, residing at Spencer, in the county of Worcester and State of Massachusetts, have invented new and useful Improvements in Ice-Cream-Cone Dispensers, of which the following is a specification.

It is the principal aim and object of this invention to provide a device of the above mentioned character designed for supporting a plurality of cones when arranged in superposed or nesting relation and permits of an easy and quick withdrawal of the lower cone and at the same time immediately engages the next adjacent cone thereabove without causing injury to the cone that is withdrawn or the lowermost cone retained in the device.

More particularly the present invention consists in the provision of a device of the above mentioned character wherein gripping plates of novel construction are resiliently and swingably supported in opposed relation to each other in such a manner that the resilient means acts to normally hold the jaws in yielding engagement with the lowermost cone yet these jaws or plates are easily spread to permit the withdrawal of the lowermost cone when desired.

It is an additional object of the present invention to provide a device of the above mentioned character wherein a main casing of an improved construction is designed to accommodate a plurality of stacks of nesting cones the lowermost of each stack of which may be readily withdrawn through the bottom of the casing when desired.

Among the other aims and objects of this invention may be recited the provision of a device of the character described with a view to compactness, and in which the number of parts are few, the construction simple and the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes

in the construction and arrangement of parts may be made without departing from the principle of operation of the various parts.

The invention is clearly illustrated in the accompanying drawings, in which:

Figure 1 is a side elevation of the device.

Fig. 2 is a vertical sectional view thereof.

Fig. 3 is a horizontal sectional view taken on line 3—3 of Fig. 1.

Fig. 4 is a side elevational detail of the clamping and retaining jaws or plates.

Fig. 5 is a top plan view thereof.

Fig. 6 is a sectional detail taken on line 6—6 of Fig. 5.

Fig. 7 is another detail view.

Fig. 8 is a detail perspective view of the split ring supporting the retaining jaws or plates.

Similar characters of reference are employed in all of the above described views to indicate corresponding parts.

Referring now, more particularly, to the accompanying drawings there is provided a stand or main base 1 of a cylindrical configuration the walls of which are provided with opposed pairs of openings 2 while the upper edge is flared, as at 3. Seated on the upper edge of the base or stand is a base plate 4 formed with a depending annular flange 5 which fits about the outer surface of the base or stand at the upper edge and this plate is provided with a central opening 6 and is also provided with a large opening 7 for a purpose that will presently appear. A vertical rod 9 is employed and has its lower threaded extremity 10 disposed through the opening 6 and this threaded extremity is engaged by a nut 11 which is positioned above the base plate and contacts therewith so as to support the rod while the extreme free end of the rod is engaged by another nut 12 which cooperates with the nut 11 in clamping the rod rigidly to the base plate.

The main casing generally indicated by the numeral 13 is employed and may be of a hexagonal configuration in cross section being desirably formed of wood and provided in each of the flat faces with door openings 14 in which are swingably mounted glass doors 15. Carried in the rear of each of the openings 14 are independent cone receiving chambers 16. Joined with the upper and lower edges of the casing 13 at the inner periphery thereof are the arms

17 of spiders 18 the eyes 19 of which rotatably engage the rod. In this connection it is to be observed that the lower edge 20 of the casing is inset from the upturned annular flange 21 on the base plate 4.

In order to support the upper end of the casing and cover the same a nut 22 is engaged on the threaded extremity 23 of the projecting end of the rod and serves as a 10 rest for the conical cover 24 which is provided with an opening at its apex so as to be disposed about the rod while the lower flanged end 25 is positioned in surrounding relation with the upper end of the casing. 15 A top nut 26 is engaged on the extreme threaded extremity of the rod 9 and insures the retention of the cover 24 in position.

With a view toward providing improved means for releasably retaining stacks of 20 cones in the chambers 16 an open ring 27 is employed and is formed at diametrically opposite points with straight portions 28. A pair of opposed arcuate clamping and retaining jaws or plates 29 are provided for 25 the ring and are formed medially of the upper edges with sleeves 30 which are pivotally engaged about the straight portions 28 so that the jaws or plates may swing on the ring. Spring members generally indicated by the numeral 31 are employed and are each formed from a single piece of wire bent intermediate its ends into a substantially U-shaped configuration providing 30 spaced side arms 32 and an intermediate portion 33 the side arms being bent outwardly as at 34 near the intermediate portion 33 so that the spring members will readily embrace the jaws or plates. The arms 32 are formed medially of their ends 35 with coils 35 which are disposed about the flat portions 28 while the free angularly projecting terminal portions 36 of the side arms bear against the base plate near the intermediate portion 37 of the ring. The 40 ring is secured to the base plate, as by soldering the terminals 38 to the under face thereof, the diametrically opposite portion of the ring resting in the flared portion 3 of the base 1, the spring members are tensioned so as to normally hold these jaws or 45 plates toward each other yet may be easily spread when pressure is exerted thereagainst. Subsequent to the application of the supporting ring, the clamping jaws 50 which are positioned in alinement with the opening 7, the main casing is swung so that one of the compartments 16 alines with the opening 7 whereupon the doors 15 may be opened and a stack of nesting cones 40 disposed therein while the lowermost cone 41 will project through the opening 7 and lie between the jaws of the adjacent retaining device and be supported by the latter until such time as it is desired to remove the 55 lowermost cone. In removing the lower-

most cone it is only necessary to grasp the same and pull it downwardly against the jaws or plates 29 which move away from each other against the tension of the spring members 31 and these members remain until 70 the lowermost cone has been entirely withdrawn but as soon as this occurs springs 31 act to retain the jaws in close relation with each other and in yielding engagement with the outer surface of the next cone. These 75 spring members 31 are sufficiently strong to prevent accidental passage of the stack of cones therebetween yet will not cause breakage or other injury to either the cone being withdrawn or the cone following. 80

What is claimed is:

1. A device of the kind described including a stand formed with opposed openings in its wall and provided with a flared upper edge, a base plate seated on the upper edge of the stand and formed with a central opening and with a relatively large opening to one side of the center, a vertically disposed rod mounted in the center opening of the base and secured to the latter 90 by clamping nuts disposed relatively against the upper and lower faces, a casing having vertically disposed outwardly opening doors giving access to the plurality of compartments concentrically disposed with 95 reference to said rod, spiders having their arms connected to the walls of the casing at the upper and lower end and rotatably engaging the rod, a removable cover for the casing clamped to the upper end of the rod, 100 the compartments registering with the large opening in the base upon the rotation of the casing and being designed each to receive a stack of nested cones, a retaining device embodying a supporting ring secured 105 to the base in surrounding relation to the large opening therein, and opposed resiliently mounted jaws carried by the ring.

2. An ice cream cone dispenser comprising in combination with a stand flared at 110 its upper end, a base plate seated on the upper edge of the stand and provided with a cone receiving opening, a retaining device consisting of an open ring having terminals secured to the base plate on the under face thereof, the diametrically opposite portion of the ring resting in the flared portion of the stand, the ring being in surrounding relation to said opening, a pair of arcuate tapering jaws swingingly connected 115 to said ring at diametrically opposite sides, and U-shaped spring members carried by the ring and terminally bearing respectively against the under face of the base plate and the outer faces of the jaws to exert a tension on the latter for the purpose specified. 120

In testimony whereof I affix my signature.

GIROLAMO SOLDANI.
